UNITED STATES PATENT OFFICE.

HENRY JAMES BLEDSOE, OF BROWNSVILLE, TENNESSEE.

DESIGN FOR A MAIL BOX.

Application filed November 19, 1928. Serial No. 28,947. Term of patent 3½ years.

To all whom it may concern:

Be it known that I, HENRY J. BLEDSOE, a citizen of the United States, residing at Brownsville, in the county of Haywood and State of Tennessee, have invented a new, original, and ornamental Design for a Mail Box, of which the following is a specification, reference being had to the accompanying drawing, forming part thereof, which is a perspective view of a mail box showing my new design.

I claim:

The ornamental design for a mail box, as shown.

HENRY JAMES BLEDSOE.
